Patented Jan. 14, 1958

181,911

AIR CONDITIONER CABINET FRONT OR SIMILAR ARTICLE

Jean O. Reinecke, Oak Park, Ill., assignor to Amana
Refrigeration, Inc., Amana, Iowa, a corporation of
Iowa

Application December 3, 1956, Serial No. 44,047

Term of patent 7 years

(Cl. D62—4)

FIG. 1.

3

FIG. 2.

Figure 1 is a front elevation of an air conditioner cabinet front or similar article showing my new design, the center panel being hatched to indicate fabric;

Figure 2 is a top plan view thereof;

Figure 3 is a cross-sectional view taken on line 3—3 of Figure 1; and

Figure 4 is a side elevational view of the air conditioner cabinet front.

I claim:

The ornamental design for an air conditioner cabinet front or similar article, substantially as shown.
